UNITED STATES PATENT OFFICE.

RUSSELL PARKER, OF BROOKLYN, NEW YORK.

LIQUID-PISTOL.

SPECIFICATION forming part of Letters Patent No. 600,552, dated March 15, 1898.

Application filed July 22, 1897. Serial No. 645,519. (No model.)

To all whom it may concern:

Be it known that I, RUSSELL PARKER, of Brooklyn, in the county of Kings and State of New York, have invented a new and useful Improvement in Weapons, of which the following is a specification.

My invention consists of an improvement in weapons, with the object in view of providing a weapon which may be used to protect a person by the discharge from the weapon of ammonia or other liquid at the will of the operator.

A further object is to provide an ammonia-pistol which will bear a close resemblance to a firearm, such as a pistol or a revolver.

A practical embodiment of my invention is represented in the accompanying drawings, in which—

Figure 1 represents a perspective view of my improved weapon. Fig. 2 represents a vertical central longitudinal section through the same. Fig. 3 is a transverse vertical section in the plane of the line 3 3 of Fig. 2, and Fig. 4 is a transverse section in the plane of the line 4 4 of Fig. 2.

The stock or butt of the weapon is denoted by A, and it is provided with a forwardly-extended barrel B. The stock A is extended forwardly a short distance beneath the barrel B, as shown at a, to represent a chamber, the front of the said extension a being provided with an end plate a', having a plurality of suitable circular holes a² therethrough. The stock A is further provided with a rearwardly and downwardly extended portion a³, which forms a suitable grip or handle for the operator, the material which forms the handle being cut away upon each side of the same for the projection therethrough of the sides of the bulb, a metallic strap being thereby formed for the reception and retention of the said bulb.

The collapsible bulb C is located within and fitted to the handle or grip portion a³ of the stock A, which bulb is adapted to form a reservoir for the ammonia or other liquid which it is desired to carry within the weapon. The upper and lower portions of the bulb are adapted to fit snugly between the opposite portions of the strap above described for holding the said bulb against lateral displacement within the handle portion of the stock.

The bulb C is provided with a flexible delivery-tube c, which extends from the said bulb C through the stock A into the barrel B and is there provided with a suitable discharge-nozzle c', located near the mouth of the barrel.

The trigger is denoted by D, the finger portion d being extended downwardly through the bottom wall of the chamber A of the butt, the said bottom wall of the chamber serving as a pivot upon which the trigger is rocked. The upper end d' of the trigger is extended upwardly through an elongated slot b in the bottom wall of the barrel B into the interior of the barrel, where the said trigger is adapted to compress and release the delivery-tube c. The trigger is provided with a shoulder d², preferably formed by bending the trigger at a point within the stock A between the retraction-spring and the finger portion d for holding the trigger in its operative position within the weapon, thereby doing away with the necessity of providing a special pivot-pin for the said trigger.

The stock A is preferably provided with a shoulder a⁴ opposite the upper end d' of the trigger D, between which the delivery-tube c is compressed. The tube c is yieldingly held closed or compressed, and the upper end of the trigger is held thereby at the limit of its rearward movement by means of a suitable retraction-spring E, which in the present instance consists of an elastic band of loop form which passes around the trigger D within the stock A and also around a suitable lug or pin e, secured to the bottom wall of the said stock.

The stock A may be provided with a suitable guard F for protecting the finger-piece d of the trigger D.

In operation when it is desired to use the weapon the bulb C is compressed, thereby tending to force the liquid contained therein out through the delivery-tube c. At the same time the finger portion of the trigger may be pulled backward, thereby permitting the escape of the liquid through the tube c and out through the nozzle c' in the form of a small stream or spray. The moment it is desired to stop the operation the bulb C may be released and permitted to again expand into its normal position, and the trigger may also

be released to again compress the tube *c* and prevent the escape therethrough of the remaining liquid.

The slot *b* in the barrel *B* serves to guide the upper portion of the trigger in its forward and backward movement.

While I have described this weapon as being an ammonia-pistol, it is evident that it is adapted for use for discharging any suitable liquid which may be contained within the bulb.

This weapon when used as an ammonia-pistol is particularly applicable for use by cyclists, as the stream or spray of ammonia may be discharged to a great distance by the pressure of the bulb, thereby rendering the pistol an effective weapon for use against dogs or even against highwaymen, foot-pads, and the like, the discharge of the ammonia serving to temporarily blind the person or animal which it strikes. The shape of the weapon also serves to render it more effective as a means of defense.

It is evident that slight changes might be resorted to in the construction and arrangement of the several parts without departing from the spirit and scope of my invention. Hence I do not wish to limit myself strictly to the structure herein set forth; but

30 What I claim is—

1. A pistol-like implement provided with a compressible fluid-receiving chamber, a compressible discharge-tube leading from the said chamber and means for opening and closing the discharge-tube.

2. A weapon comprising a barrel, a stock, a collapsible bulb located within the stock provided with a flexible delivery-tube extending into the barrel, a trigger in position to

40 open and close the delivery-tube and a re-

traction-spring engaging the trigger to yieldingly hold the tube closed, the said trigger having a shoulder between its finger portion and the spring for retaining the trigger in its operative position within the weapon, substantially as set forth. 45

3. A weapon comprising a barrel, a stock, a collapsible bulb located within the stock and provided with a flexible delivery-tube extending into the barrel and a trigger adapted 50 to open and close the said delivery-tube for permitting the escape of the liquid from the bulb and retaining it within the same at pleasure, substantially as set forth.

4. A weapon comprising a barrel, a stock, 55 a collapsible bulb located within the stock and projecting through the sides thereof, the said bulb being provided with a flexible delivery-tube extending into the barrel and a trigger normally holding the tube closed in 60 position to open the tube when rocked in one direction, substantially as set forth.

5. A weapon comprising a barrel, a stock having a shoulder thereon, a collapsible bulb seated within the stock, the said stock being 65 cut away to expose the bulb, a delivery-tube extending from the bulb into the barrel and a trigger having a finger-piece extending without the stock and an upwardly-extended portion adapted to normally compress the 70 tube against the said shoulder on the stock, the said trigger when rocked in one direction serving to open the said tube to permit the discharge of liquid from the bulb, substantially as set forth.
